(57) CLAIM

The ornamental design for the floor cleaning device, as shown and described.

DESCRIPTION

FIG. 1 is a front perspective view of the new ornamental floor cleaning device of the present invention.

FIG. 2 is a front view thereof.

FIG. 3 is a rear view thereof.

FIG. 4 is a left side view thereof.

FIG. 5 is a right side view thereof.

FIG. 6 is a top view of the cleaning head of the present invention.

FIG. 7 is a bottom view of the cleaning head of the present invention.

FIG. 8 is an enlarged perspective view thereof, showing the handle shortened, and cleaning head separate for clarity of disclosure.

FIG. 9 is a front perspective view of a second embodiment of a floor cleaning device.

FIG. 10 is a front view of the alternate embodiment.

FIG. 11 is a rear view of the alternate embodiment.

FIG. 12 is a top view of the cleaning head of the alternate embodiment.

FIG. 13 is a bottom view of the cleaning head of the alternate embodiment; and,

FIG. 14 is an enlarged perspective view thereof, showing the handle shortened, and cleaning head separate for clarity of disclosure.
